(No Model.)

A. P. TRAVIS.
CAR SEAL.

No. 485,070.

Patented Oct. 25, 1892.

UNITED STATES PATENT OFFICE.

ALBERT P. TRAVIS, OF GRUNDY CENTRE, IOWA.

CAR-SEAL.

SPECIFICATION forming part of Letters Patent No. 485,070, dated October 25, 1892.

Application filed June 12, 1891. Serial No. 396,015. (No model.)

To all whom it may concern:

Be it known that I, ALBERT P. TRAVIS, of Grundy Centre, in the county of Grundy and State of Iowa, have invented certain new and useful Improvements in Car-Seals; and I do hereby declare the following to be a full, clear, and exact description of the invention, such as will enable others skilled in the art to which it appertains to make and use the same.

10 My invention relates to an improvement in car-seals, the object being to provide a simple device for sealing car-doors; and it consists in certain novel features of construction and combinations of parts, as will be herein-
15 after described, and pointed out in the claims.

In the accompanying drawings, Figure 1 is a view in elevation of my improved seal, showing a portion of a freight-car and door to which the same is applied. Fig. 2 is a vertical section through the seal and pin. Fig. 3 is a view on line α α of Fig. 2, and Fig. 4 is a view of one of the seals.

A represents a bracket-iron, the same having several bolt-holes 1 1 to receive bolts or screws, by which to fasten the bracket in place on the car or, if occasion should require it, to the door. This bracket is provided with lugs or ears 2 2, located a suitable distance apart to receive the hasp between them.

30 B indicates the hasp. This hasp is secured in the usual way by a staple or other device to the door, (or car-body, as the case may be.) The hasp is provided with a boss 4 at or near its free end, and the latter is adapted to fit 35 between and coincide with the lugs or ears 2 2. A hole 6 is formed through these parts for the reception of a pin for holding the parts together.

C is the pin. This pin is fitted to the hole 40 6 and provided with an annular groove 7 at a point opposite the boss 4 when inserted within the hole 6, and this groove is adapted to receive a portion of the seal. The boss 4 is provided with slits 8 8 at the lower edge.

45 D is a seal. This may be of any thin material, such as sheet metal, card-board, or stiff paper. The seal is formed substantially as shown. It consists of a narrow strip of material with a slit 9 cut therein parallel with 50 one edge. This slit extends nearly to one end

of the seal, in order that the seal may be conveniently broken at this point when it is desired to remove it to open the door. The strip is preferably about the same width as the boss, and the portion 12 of the seal is 55 adapted to be inserted in the slits 8 8 edge-wise, the main or wide portion 13 being adapted to serve as a label, if desired. The idea is to have the narrow portion 12 spring into the annular groove 7 when the pin is inserted in the hole 6. The pin is provided with a tapering point 14, which when inserted in the hole 6 forces the portion 12 of the seal to one side into the enlargement formed in the bore of the boss. As the pin fits in the 60 hole 6 it is necessary for the corrugation 16, previously formed in the part 12 of the seal, to drop to one side until the groove comes opposite it, after which the corrugated part 16 springs into the groove and locks the pin 65 in place, from which it cannot be removed without first breaking the seal, thus disclosing the fact that the car has been opened.

To get the seal in shape for use before sealing, it may be placed in position in the slits 70 of the hasp, as before, without first inserting the boss between the lugs or ears. The pin may then be forced part way into the boss, but not far enough to allow the portion 12 to spring into the groove, and the seal will thus 75 be bent into shape. After this the parts are placed in position and locked. The hasp is provided with a handle 17 at its free end, by which the hasp is manipulated.

It is evident that slight changes might be 80 resorted to in the form and arrangement of the several parts described without departing from the spirit and scope of my invention, and hence I do not wish to limit myself to the exact construction herein set forth; but,

Having fully described my invention, what I claim as new, and desire to secure by Letters Patent, is—

1. The combination, with a bracket and a hasp having a boss thereon, of a pin adapted 90 to enter openings in the bracket and boss and a seal adapted to enter a recess in the pin and lock the latter in place, substantially as set forth.

2. The combination, with a bracket and a 95

hasp having a boss formed thereon, of a pin
adapted to enter openings in the bracket and
boss and a seal adapted to enter a slit in one
of said parts and drop into a notch in the pin,
5 whereby the latter is locked in place, substan-
tially as set forth.

In testimony whereof I have signed this

specification in the presence of two subscrib-
ing witnesses.

ALBERT P. TRAVIS.

Witnesses:

CHAS. O. JONES,

JOHN A. BELKNAP.
